UNITED STATES PATENT OFFICE.

SAMUEL M. WEAVER AND WILLIAM AMBLER, OF CLEVELAND, OHIO.

ATTACHMENT FOR ELECTRICAL FURNACES.

No. 867,542.

Specification of Letters Patent.

Patented Oct. 1, 1907.

Application filed September 29, 1905. Serial No. 280,593.

To all whom it may concern:

Be it known that we, SAMUEL M. WEAVER and WILLIAM AMBLER, residing at Cleveland, in the county of Cuyahoga and State of Ohio, have invented certain new and useful Improvements in Attachments for Electrical Furnaces, of which the following is a full, clear, and exact description, reference being had to the accompanying drawings.

This invention relates to attachments for use in connection with electrical furnaces employed by dentists in baking porcelain fillings for crown and bridge work, and is especially designed to be used with a thermo-pile.

More specifically the invention contemplates the use of an attachment to rest upon the bracket in front of the door of an electrical furnace, and provided with a thermo-pile adapted to project into the same, and when heated to generate a current which can be measured by any suitable device, and thus obtain a means for determining the amount of heat within the furnace. All of this construction is old and well known in the art but there are numerous disadvantages associated with this system due to the fact that the temperature in the furnace at the ends of couples of the thermo-pile may not be the temperature of that portion of the furnace where the porcelain is located. This is especially true when the thermo-pile is removable, since when it is withdrawn and again inserted there may be some variation in the extent to which it is inserted, and hence the reading of the measuring device would not correctly indicate the heat which is acting upon the porcelain on account of the change in the relative positions of the two. Or in the case where the thermo-pile is made rigid with the furnace there is no very practical way of insuring the placing of the porcelain exactly under the couples especially when it is removed for inspection or for any other cause such as cooling for the purpose of maintaining it at substantially a constant temperature.

It is the object of this invention therefore to arrange in conjunction with a removable thermo-pile, a pan or tray which has a fixed relationship with respect to the same whereby the piece of porcelain may be placed in position with respect to the thermo-pile and can be retained in this position throughout the entire baking process.

The invention also relates to a suitable device for supporting the entire mechanism in such a manner that the pan and the thermopiles may be readily swung into the furnace and when removed may be handy for the operator.

The invention may be further briefly summarized as consisting in the construction and combination of parts hereinafter set forth in the following description, drawings and claims.

Referring to the drawings, Figure 1, represents a side

elevation of an electrical furnace with the thermo-pile swung out of the same; Fig. 2 is a vertical section through the center of the device; Fig. 3 is a front elevation, partly in section, of a modified form of the device, and Fig. 4 is a side elevation of the same.

Any preferred form and construction of electrical furnace and thermo-pile attachment may be employed in the carrying out of my invention so long as they possess the necessary characteristics, but we have shown one form in the drawings which very effectively meets the requirements, and in such embodiment 1 represents a furnace having a suitable fire place 2, shown in dotted lines in Fig. 1, and opening out at the front. The furnace 1, is provided just at the entrance 70 to the fire place with a bracket 3, for supporting work or tools as the case may be. The front of the furnace is further provided with a bearing bracket 4, as shown, to which is secured a pin 4^a, having pivoted to it a swinging arm 5, provided with a handle 5^a, and adapted to support the thermo-pile attachment.

The thermo-pile attachment consists of the casing 6, provided upon its back with a suitable opening 6^a, which receives the arm 5. A thumb screw 6^b, screwing into the casing is arranged to take against the arm 5, 80 and hold the same in any adjusted position. The casing 6, is preferably made hollow and is packed with fire clay 7, and through this and the casing 6, project the thermo-couples 8, of ordinary construction. These couples 8, extend out from the front of the face of the fire clay portion as shown. Near the base of the casing 6, the fire clay portion 7, is provided with a recess 7^a, for the purpose of receiving the end of a tray or pan 9, which projects out beyond the same under the active ends of the couples, whereby any thing placed upon 90 the pan 9, will be under the thermo-couples. Screws 9^a, threaded into the casing 6, pass through the fire clay portion and engage the pan for the purpose of holding the same rigidly in the casing.

It will be seen from the foregoing that the porcelain filling, or other article, may be placed upon the pan under the thermo-couples, and the arm 5, be swung so as to project the pan, work and the thermo-couples into the fire place where the filling can be thoroughly baked and the amount of heat acting upon 100 the same can be kept constant by means of any suitable measuring device connected to the thermo-pile which will indicate the amount of current generated by it. Should the measuring device indicate too great a current, or a current which is considered sufficient to impair the pigments in the filling, the arm 5, may be swung upon its pivot and the filling may be allowed to cool in the open air. After the filling has cooled sufficiently it may again be inserted in the fire place to finish the baking.

In the modification shown in Figs. 3 and 4, the casing 10, is provided with an opening at the bottom to

receive the pan or tray 11, and the edges of the casing at the opening are inclined as shown at 12, for the purpose of receiving the dove-tailed portion of the tray. By this construction it will be seen that the tray may be slid into the opening in the bottom of the casing and will be firmly held therein by the inclined sides and the dovetailed construction of the pan. In this embodiment the casing is also provided with a spring clip 13, adapted to take under the bracket of the furnace and hold the device in place. A handle 14, is secured to the rear side of the casing and the thermo-couples are arranged to pass through it.

Having described our invention we claim:—

1. In an attachment for a furnace, the combination with a thermo-pile, of means for supporting the work in a fixed relationship thereto.
2. In an attachment for a furnace, the combination with a heat indicating device, of means for supporting the work in a fixed relationship thereto.
3. In an attachment for an electrical furnace the combination with a thermo-pile, of means for supporting the work in a fixed relationship thereto.
4. In a furnace, the combination with an arm pivoted thereto, of means for indicating the heat in said furnace and mounted upon said arm, and means also carried by said arm for holding the work in a fixed relationship with respect to said indicating means.
5. In a furnace, the combination with an arm pivoted thereto, of a thermo-pile carried by said arm, and means

for supporting the work in a fixed relationship to said thermo-pile.

6. An attachment for an electrical furnace, consisting of a thermo-pile, and means carried thereby for supporting the work in a fixed relationship thereto.

7. In an attachment for an electrical furnace, the combination with the casing, of a fire clay portion carried thereby, thermo-couples mounted in said fire clay portion, and means carried thereby for supporting the work in a fixed relationship to said thermo-couples.

8. In an attachment for an electrical furnace, the combination with the casing, of thermo-couples carried thereby, and a pan mounted in said casing for supporting the work in a fixed relationship to said couples.

9. In an attachment for an electrical furnace, the combination with the casing, of a fire clay portion carried by said casing, thermo-couples projecting from the face of said fire clay portion, a pan carried thereby and adapted to support the work in a fixed relationship to said couples.

10. In an attachment for an electrical furnace, the combination with the casing, of a fire clay portion within said casing and provided with a recess, thermo-couples projecting from the face of said fire clay portion, a pan mounted in said recess, and set screws for holding the same in place.

In testimony whereof we affix our signatures in the presence of two witnesses.

SAMUEL M. WEAVER.
WILLIAM AMBLER.
